UNITED STATES PATENT OFFICE.

FRANK M. PRESTWICH, OF NEW YORK, N. Y.

CUFF.

1,241,479.

Specification of Letters Patent. Patented Sept. 25, 1917.

Application filed April 6, 1916. Serial No. 89,276.

To all whom it may concern:

Be it known that I, FRANK M. PRESTWICH, a subject of the King of England, and resident of New York, in the county of New 5 York and State of New York, have invented certain new and useful Improvements in Cuffs, of which the following is a specification.

My invention relates to apparel and is 10 herewith disclosed as applied to a reversible cuff. Such cuffs have been made in the past, but unless starched, so that all the layers of the cuff adhere together, they lack the attractive appearance which they should 15 have if they are to be widely used. I have discovered that an unstarched cuff can be made equally attractive if the interlining is properly arranged, and this arrangement mainly resides in making the interlining in 20 such a way that it will be less conspicuous when the cuff is folded. To obtain this result it is frequently advantageous to diminish the thickness of said interlining at the fold of the cuff while giving it its full thickness elsewhere or to make the interlining 25 heavier on the free flap of the cuff.

Other features and advantages will hereinafter appear.

In the accompanying drawings—

Fig. 1 is a perspective view of one of my 30 cuffs as worn with the extra face turned in.

Fig. 2 is a side view of the cuff partly broken away.

Fig. 3 is a view of a modification, but 35 otherwise like Fig. 2.

Fig. 4 is a face view, partly broken away, of the cuff shown in Figs. 5 and 6.

Fig. 5 is a section of a cuff embodying all 40 the advantages of the alternative forms,—this view being largely diagrammatic and expanded for clearness.

Fig. 6 is a view similar to Fig. 5, but shows the cuff folded.

My cuff is shown as stitched to a sleeve 1 and it comprises two faces each having a 45 complete covering 2, 3, of the outside material,—said material being usually that of which the body of the shirt is made. To make the cuff, the outside thicknesses cut to 50 the right shapes, are first stitched together, back sides out, by a seam 4, and then turned inside out. One or more interlinings are then placed inside the bag so formed, the interlinings closely conforming to the edges 55 of the bag and placed between the inwardly

projecting ends 6, 7 of the material. The interlinings are then stitched into place by running a seam or stitching 8 near the edge of the bag, so that this seam will bind together the ends 6 and 7 and hold the interlinings 12, 13 and 15 between them, one long side however being left open. This long side is then stitched to the sleeve by an extension of the seam or stitching 8 which passes through the sleeve, and at the same 60 time sews up the open cuff. In order to get the proper effect the end of the sleeve is doubled over, and the seam 8 passes through the whole cuff and the sleeve. The seam 8 comes close to the end of the doubled over 65 part of the sleeve, thus completely concealing it. By having the seam 8 set in from the edge of the cuff as is usual, the cuff edge 11 will seem to be the edge of a turned over cuff thus making the appearance of the free 70 cuff identical whichever way it is folded and worn.

In order to obtain the right kind of a fold where the cuff is folded over, I modify 75 the interlinings at this point. For this purpose I have found it advantageous to either eliminate one interlining at this point or to make the interlinings comparatively light. The utility of this arises partly from the fact 80 that if the cuff is folded one way the outside face should be longer than the inside, while when the same cuff is folded the opposite way that same face should be shorter. By providing a weak place in the interlining, I make it possible for the outside face to 85 draw itself taut across the inside face so as to avoid crinkling it. This avoiding of crinkling is apparently due to the fact that the relative weakness of the cuff at the fold 90 makes all attempted crinkling take place in 95 such a confined place that there is no crinkling at all properly so called, because the inside face of the cuff is pinched between the slightly distant thicker portions of the interlining. In other words one face becomes 100 sort of a hinge for the other, of which the butts are formed by the extra thicknesses of the adjacent interlining. These functions are possible because the unstarched cuff permits the faces to slide over the interlining and each other, and this would not 105 be possible in a starched cuff, because the starch cements the faces to each other and to the interlining.

In Fig. 2 I have shown this interlining 110

as made from two entirely separate pieces of cloth 12 and 13, each of which, as seen at Figs. 2 and 3, covers almost half of the cuff; these pieces, however, fail to quite meet, thus forming a little pocket in which the inside covering 2 doubles up slightly and forms a pintle of a hinge. Each piece of interlining 12 and 13 is advantageously formed of a single piece of thin muslin or equivalent material, of which the edges are caught in the outside seam 8. These interlining pieces should be made of very light material, and should approximate in flexibility to the covering material of the cuffs so that they will be inconspicuous. Unless this is carefully provided for, the cuff will lose its natural soft effect. The interlining is advantageously kept in place by being stitched to one face of the cuff by a seam 21 or else the interlining is kept in place by lighter material stitched by a seam 17 forming a holding means 18 extending from one interlining to the other. Where the interlining is stitched to the other face the seam 21 makes the cuff appear a different style on that face from what it does on the other thus enabling the wearer to give the impression of wearing two different shirts when wearing the cuff the two ways. Thus the interlining is not a padding as it would be in a starched cuff, but is a spring backing.

For some forms of material it is advantageous to make the interlining continuous, but to weaken it at the fold of the cuff. This may be obtained by perforating the interlining along the edge of the cuff. I have shown in Fig. 3 how this may be done with advantage by having interlinings 12 and 13 but not coming up to the fold of the cuff by a considerable fraction of an inch, or even by a greater amount. The interlinings 12 and 13 are stitched by a very inconspicuous seam 17 to an intermediate or extension interlining 18 which extends part way over each. The outer faces completely conceal these inside seams and thus give the cuff a very attractive appearance.

In order to get the best effect, I find it advantageous to have one part of the interlining heavier than the rest, and to obtain this advantage this heavier lining must be on the flap of the cuff which is free of the sleeve. This heavier section is formed by an extra or reinforcing piece 22 stitched by seams 23 to the interlining of which it forms a part.

The whole combination is shown in Fig. 4, of which Figs. 5 and 6 are diagrammatic sectional views. In these figures the perforated interlining 15 extends completely from one end of the cuff to the other and is perforated at 19. Adjacent along the rectangular perforations on the outer flap of the cuff, is the reinforcing piece 22 making this flap heavier. This reinforcing piece

need not cover the whole flap since its principal function is to give stiffness to the free flap adjacent the fold. The two half interlinings 12 and 13 are held together by the intermediate weaker interlining, and may in addition be stitched by the stitching 21 to the adjacent face of the cuff, thus combining the advantages of construction shown in Figs. 2 and 3, while the interlining 15 and reinforcing 22 give the advantages mentioned above for them. It will be noted that the opening between the interlinings 12 and 13 extends out into the seams at the edges of the cuff, as most clearly seen in Fig. 2, with the result that said seams naturally tend to fold at the proper point when the cuff is folded; this being so because said opening forms a thin place within the seam. Furthermore, the interlining 18 (also shown in Fig. 5) which overlaps the interlinings 12 and 13 on each side of the fold, reinforces the interlinings and thus stiffens the cuff at the fold without making it bulky elsewhere. It should be remembered that Figs. 5 and 6 are merely diagrammatic, and that in the cuff as made the interlinings and faces touch each other and are stitched together at the ends and to the sleeve as described above to get the flap effect where the sleeve joins the cuff.

The cuff includes two buttonholes along each edge of the usual form.

While I have described certain features of my invention in great detail, I have done so only to enable those skilled in the art to appreciate some advantages of my invention, but what I claim as my invention is:

1. A reversible cuff, foldable in either direction upon itself, so as to provide a flap for attachment to a sleeve and a free flap adapted to lie against either face of the attachment flap; said cuff comprising two outer faces stitched together along their marginal edges, a separate interlining piece for each flap of the cuff, said interlining pieces substantially coming up to the fold line of the cuff but slightly spaced apart at such line, and means within the cuff for holding said interlining pieces in place at the fold and permitting said outer cuff faces to slide freely relative to each other at the fold.

2. A reversible cuff, foldable in either direction upon itself, so as to provide a flap for attachment to a sleeve and a free flap adapted to lie against either face of the attachment flap; said cuff comprising two outer faces stitched together along their marginal edges, an interlining piece for each flap of the cuff, said interlining pieces substantially coming up to the fold line of the cuff but lightly spaced apart at such line, and an interlining joining the first-mentioned interlinings for holding the same in place at the fold and permitting said

outer cuff faces to slide freely relative to each other at the fold, and which is perforated at the fold of the cuff.

3. A reversible cuff, foldable in either direction upon itself, so as to provide a flap for attachment to a sleeve and a free flap adapted to lie against either face of the attachment flap; said cuff comprising two outer faces stitched together along their marginal edges, a separate interlining piece for each flap of the cuff, said interlining pieces substantially coming up to the fold line of the cuff but slightly spaced apart at such line, and an additional interlining piece 15 bridging the space between the first-mentioned interlining pieces and overlapping and stitched to the latter to hold them in place.

4. The combination with a sleeve, of a 20 foldable cuff having outer faces foldable on themselves, a reinforcement lying on the free flap portion of said cuff and terminating along the folding edge, an interlining overlapping said reinforcement and stitching 25 ing for holding said reinforcement and interlining in place.

5. A reversible cuff, foldable in either direction upon itself, so as to provide a flap for attachment to a sleeve and a free flap adapted to lie against either face of the 30 attachment flap; said cuff comprising two outer faces stitched together along their marginal edges, an interlining piece for each flap of the cuff, said interlining pieces coming substantially up to the fold line of 35 the cuff but slightly spaced apart at said line, a weaker interlining joining the first-named interlinings for holding the same in place at the fold and permitting said outer cuff faces to slide freely relative to each 40 other at the fold, and an additional interlining covering substantially the entire face of the cuff, and which is perforated at the fold of the cuff.

Signed at 39 E 42nd st. in the county of 45 New York and State of New York this 3d day of April A. D. 1916.

FRANK M. PRESTWICH.
